CENTER STRIPE SPRAY BAR

Harry S. Wallace, Pecos, Tex.

Application August 3, 1950, Serial No. 177,464

7 Claims. (Cl. 299—25)

1

This invention relates to a center stripe spray machine for spraying white lines along the center of a road.

This application is a continuation in part of my copending application filed July 11, 1947, with the Serial Number 760,225, and now abandoned.

It is an object of the present invention to provide a machine for spraying white lines along the center of a road which is provided with mechanism for timing the spraying of intermittent lines along opposite sides of a full center line wherein the stripe portions of the intermittent lines will be staggered respectively with the stripe portions of opposite intermittent lines.

Other objects of the present invention are to provide a center stripe spray machine which is of simple construction, easy to operate and efficient in operation.

For other objects and for a better understanding of the invention, reference may be had to the following detailed description taken in connection with the accompanying drawing, in which

Figure 1 is an elevational view of a truck body with the center stripe mechanism of the present invention mounted thereon.

Figure 2 is an enlarged cross-sectional view taken on line 2—2 of Figure 1.

Figure 3 is a fragmentary longitudinal cross-sectional view taken on line 3—3 of Figure 2.

Figure 4 is a fragmentary longitudinal cross-sectional view taken on line 4—4 of Figure 2.

Figure 5 is a side elevational view of the electric timing device for controlling the operation of the magnetic paint dispensing valve.

Figure 6 is an enlarged cross-sectional view taken on line 6—6 of Figure 5.

Figure 7 is a fragmentary and longitudinal cross-sectional view taken through the timing mechanism and the driving gear therefor.

Figure 8 is an illustrative view of a highway having a full center line and intermittently spaced lines at opposite sides of the center line.

Figure 9 is a diagrammatic showing of the electric control circuit used in the mechanism.

Referring now to the figures, 15 represents a truck chassis having a cab 16 from which the truck is driven. The operator in the cab 16 will locate a guide wheel 17 carried on a forwardly extending structure 18 on a center line which is to be painted. On the end of the truck chassis 15 there is mounted a tank 19 which is filled with the paint to be used. The paint is delivered to a spreading device 21 by a pump 22. The spreading device has outlets which are controlled by

2

magnetic valve arrangements 23. The spreading device 21 is mounted on a slide, Figure 2, as indicated at 24 and controlled by a wheel 25 located at an operator's station 26.

5 The slide 24 is mounted on a transverse guide member 27 which is connected to the opposite sides of the truck frame as indicated at 28. Depending from the slide 24 are pipe members 29 in which are telescopically adjusted rods 31 which 10 are connected to a transverse frame 32. Accordingly the spreader which includes the frame 32 can be mounted for vertical adjustment on the slide 24. The spreader further includes a transversely extending pipe 33 connected by a pipe 34 leading from a strainer 35. The paint carrying pipe 33 is mounted in hubs 10 and 11 on the lower ends of downwardly extended ends of the frame 32. The pump 22 delivers the paint to the strainer 35. Paint accordingly is passed through the pipe 33 under pressure. This pressure will be indicated by a gauge 36. Such paint which is not dispensed through holes 37 of the pipe 33 will be returned to the tank 19 past valve 37' and through pipe 38 to the top of the tank 19. By 20 regulating valve 37' the pressure within the pipe 33 can be controlled.

25 On the pipe 33 are a plurality of perforated sleeves 41, 42 and 43. These sleeves are extended over the slots 37 in the pipe 33 and are rotated 30 on the pipe to cause an outward flow of paint through openings 44. Each of the sleeves have an arm 45 extending upwardly therefrom and connected to a threaded shaft 46 extending from a solenoid 47. An adjustable stop 48 will align 35 the hole 37 with the perforations 44 of the sleeve. On the top of the solenoid 47 is a relay switch 49 adapted when operated to close the circuit for the solenoid 47. This relay 49 operates a switch arm 51, Figure 9. The outer sleeves 42 and 43 40 are operated by the solenoid arrangements. These sleeves are resiliently held in assembled relation by springs 12 and 13 positioned between the outer ends of the sleeves and the hubs 10 and 11 of the frame 32.

45 The central sleeve 41 may be operated manually by a Bowden wire 52.

50 The line formed by the central sleeve 41 is continuous and serves as the center full line which divides the road. The sleeves 42 and 43 will make intermittent lines or lines with gaps therein. These intermittent lines are preferably twenty feet in length and are separated by a space of forty feet. The sleeves 42 and 43 are turned to an open position alternately so that one mark 55 on one side of the central line will be staggered

with respect to the mark on the opposite side of the center line. As between marks on opposite sides of the center line, they will be spaced relative to one another at distances of ten feet apart. While these spacings are suggested, it will be apparent that spacings of different distances can be worked out with the arrangement.

Extending upwardly from relays 49 are cables 54 which lead to a device or time switch for controlling the operation of the sleeves 42 and 43. This time device is indicated generally at 55 and the device is mounted on top of the truck frame 15. The device 55 is driven by a shaft 56 which may extend from a speedometer or other measuring device. This shaft 56 drives a shaft 57 mounted in ball bearing units 58 within a sleeve 59 adapted to be raised by a hand control device 61 against the action of a spring 62 whereby to disengage a worm gear 63 from a gear 64 which drives a disc 65 of insulating material. The worm gear 63 is on the shaft 57. When the gear 63 is coupled with the gear 64, disc 65 is driven to cause a contact plate 66 on the face of the disc 65 to pass bridging contacts 67 and 68. The bridging contacts 67 and 68 are mounted on a bracket 59 at diametrically opposite locations. The contact plate 66 extends for one hundred and twenty degrees. As the plate 66 passes under the bridging contacts, the sleeve connected with one or the other of the solenoids 41, will be operated to stop the flow of paint. The disc 65 is timed to make one revolution for sixty feet of travel along the road. If it is desired to operate one broken line at one side of the center line, one or the other of switches 71 and 72 are pulled to open positions. The source of power for operating the solenoids and the relays 49 is a battery 73.

The operator sits in seat 26 and will operate various devices to cause the different paint stripes to be made. At the same time, he will operate the wheel 25 to shift the slide 24 and bearings 10 and 11 with the sleeves 41, 42 and 43 on the pipe 33 to keep the sleeves and their paint openings properly aligned with the center of the road.

With the parts arranged in this manner the operator may drive down the center of a highway depositing the paint to form a continuous white line in the center, and when desired, intermittent lines may be placed at the sides of the center line by the sleeves 42 and 43 and these intermittent lines may be evenly spaced.

When an island is provided in the center of a highway as illustrated in Figure 8 one of the sleeves 42 or 43 is adjusted to the closed position and the other sleeve with the sleeve 41 are adjusted laterally on the pipe 33 whereby the lines pass to the sides of the island and after passing the island the sleeves are moved back to the center.

While my center stripe machine has been described for use with white paint it will be understood that any other kind of paint may be spread therewith. An asphalt stripe may be made and colored stone dispensed thereupon whereby to provide a more permanent stripe upon the road.

While various changes may be made in the detail construction, it shall be understood that such changes shall be within the spirit and scope of the present invention as defined by the appended claims.

What is claimed is:

1. In a highway striping machine, the combi-

nation which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, a hand wheel connected to the slidable mounting means of the pipe supports for laterally adjusting the position of stripes formed by the machine, perforated sleeves rotatably mounted on the pipe and positioned to cover the slots therein, means manually actuating one of said sleeves to open the slots covered thereby, and means comprising a solenoid for actuating some of said sleeves to open the slots covered thereby.

2. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, a hand wheel connected to the slidable mounting means of the pipe supports for laterally adjusting the position of stripes formed by the machine, perforated sleeves rotatably mounted on the pipe and positioned to cover the slots therein, means manually actuating one of said sleeves to open the slots covered thereby, and means comprising a solenoid for actuating some of said sleeves to open the slots covered thereby.

3. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, a hand wheel connected to the slidable mounting means of the pipe supports for laterally adjusting the position of stripes formed by the machine, perforated sleeves rotatably mounted on the pipe and positioned to cover the slots therein, means manually actuating one of said sleeves to open the slots covered thereby, and timing means in said actuating means whereby the slots are opened at spaced intervals to provide spaced auxiliary lines on the sides of a center line.

3. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, a hand wheel connected to the slidable mounting means of the pipe supports for laterally adjusting the position of stripes formed by the machine, perforated sleeve rotatably mounted on the pipe and positioned to cover the slots therein, resilient means retaining said sleeves in assembled relation, means manually actuating one of said sleeves to open the slots covered thereby, means comprising a solenoid for actuating some of said sleeves to open the slots covered thereby, timing means in said actuating means whereby the slots are opened at spaced intervals to provide spaced auxiliary lines on the sides of a center line, and means circulating paint through said paint carrying pipe.

4. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly

from the pipe for suspending the pipe from the chassis, means slidably mounting the supports on the chassis for transverse travel of the supports in relation to the pipe suspended thereby, manual means for laterally adjusting the position of stripes formed by the machine, perforated sleeves rotatably mounted on the pipe and positioned to cover the slots therein, means manually actuating one of said sleeves to open the slots covered thereby, and means comprising a 10 solenoid for actuating some of said sleeves to open the slots covered thereby.

5. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, manual means for laterally adjusting the position of stripes formed by the machine, perforated sleeves 15 rotatably mounted on the pipe and positioned to cover the slots therein, spacing sleeves positioned between the perforated sleeves, means manually actuating one of said sleeves to open the slots covered thereby, and means comprising a solenoid for actuating some of said sleeves to open the slots covered thereby, said sleeve being positioned to slide longitudinally on the pipe with said adjustable support for lateral adjustment of said sleeves in the machine.

6. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, a V-shape bracket having depending arms with hubs on the lower ends of the arms in which the said paint carrying pipe is carried, adjustable supports extended upwardly from the bracket for suspending the pipe from the chassis, means slidably mounting the supports on the chassis for transverse travel of the supports in relation to the pipe suspended thereby, a hand

wheel connected to the slidable mounting means of the pipe supports for laterally adjusting the position of stripes formed by the machine, perforated sleeves rotatably mounted on the pipe and positioned to cover the slots therein, means manually actuating one of said sleeves to open the slots covered thereby, means comprising a solenoid for actuating some of said sleeves to open the slots covered thereby, and timing means in said actuating means whereby the slots are opened at spaced intervals to provide spaced auxiliary lines on the sides of a center line.

7. In a highway striping machine, the combination which comprises a chassis mounted on wheels, a guide wheel carried by and extended forwardly from the chassis, a transversely disposed horizontally positioned paint carrying pipe having spaced slots therein spaced below the chassis, adjustable supports extended upwardly from the pipe for suspending the pipe from the chassis, means slidably mounting the supports on the chassis for transverse travel of the supports in relation to the pipe suspended thereby, perforated sleeve rotatably mounted on the pipe and positioned to cover the slots therein, resilient means retaining said sleeves in assembled relation, means manually actuating one of said sleeves to open the slots covered thereby, means comprising a solenoid for actuating some of said sleeves to open the slots covered thereby, timing means in said actuating means whereby the slots are opened at spaced intervals to provide spaced auxiliary lines on the sides of a center line, manual means for laterally adjusting the position of the sleeves on the pipe and means circulating paint through said paint carrying pipe.
